UNITED STATES PATENT OFFICE.

JAMES C. FRENCH, OF CHICAGO, ILLINOIS, ASSIGNOR TO FREDERICK C. AUSTIN, OF CHICAGO, ILLINOIS.

TRENCH-JACK.

1,281,936.

Specification of Letters Patent. Patented Oct. 15, 1918.

Application filed January 11, 1918. Serial No. 211,461.

To all whom it may concern:

Be it known that I, JAMES C. FRENCH, a citizen of the United States of America, and resident of Chicago, county of Cook, and State of Illinois, have invented a certain new and useful Improvement in Trench-Jacks, of which the following is a specification.

This invention contemplates a novel form 10 of trench jack for use in transversely bracing the side walls of a trench, thereby to prevent the walls from caving in, and whereby the workmen may lay the tile or perform the other necessary operations at the bottom 15 of the trench. For example, in the use of a trenching machine or excavator, such as those commonly employed for making trenches for the laying of tile, or for any other purpose, it frequently becomes necessary to employ boards or planks along the sides of the trench, to keep the banks from caving in, and this is especially true when the machine is working in sandy soil. The improved jack contemplated by this invention 20 is adapted to be easily inserted between the side walls of the trench, and adjusted to hold the boards or planks in position, and may be easily removed when no longer required for this purpose.

Generally stated, therefore, the object of 30 the invention is to provide a novel and improved form of trench jack which can be easily and quickly inserted and operated to brace the side walls of the trench, and which 35 can be adjusted to suit the width of the trench, as well as readily removed when no longer needed.

A special object is to provide a trench jack of this general character in which the 40 mechanism for the operation thereof is actuated by a member upon which downward pressure may be exerted, as by placing the foot thereon, so that the mechanism will be operated and forced into position to retain 45 the opposite ends or shoes of the jack tightly in position against the side walls of the trench.

It is also an object to provide certain details and features of construction and combinations tending to increase the general effi- 50

ciency and desirability of a trench jack of this particular character.

To the foregoing and other useful ends, the invention consists in matters hereinafter set forth and claimed.

55

In the accompanying drawings:—

Figure 1 is a side elevation of a trench jack embodying the principles of the invention, showing the side walls of the trench in cross-section; the operative position of the 60 trench jack being shown in full lines, and its inoperative position in dotted lines.

Fig. 2 is an enlarged detail section on line 2—2 in Fig. 1.

As thus illustrated, the invention comprises a shoe 1 connected by a transverse pivot bolt 2 with one horizontally disposed arm 3, and another shoe 4 connected by a transverse pivot bolt 5 with another horizontally disposed arm 6, the latter being supported by a transverse pivot bolt 7 on the slide 8, so that the pivot bolt 7 forms a toggle-joint. The slide 8 is adjustably held in place on the arm 3 by the transverse bolt 9, which latter is adapted to be inserted 70 through any one of the holes 10 provided in said arm for this purpose. Also, as will be seen, the arm 6 is provided with a plurality of bolt-holes 11 for the bolt 7, whereby the latter can be adjusted to different positions on this arm. The arm 6 is extended 75 to form a lever and has its end provided with a flat member 12 which forms a foot-piece, and which serves also as a stop to engage the top of the arm 3 when the toggle-joint is forced downward.

The method of using the trench jack is as follows:—The device is placed between the side walls 13 of the trench, as shown in dotted lines in Fig. 1, and the toggle-joint 7 90 is then moved downward until the shoes 1 and 4 press against the side walls, said shoes being preferably provided with teeth 14 so that they will firmly engage the side walls. Downward pressure is then applied or exerted on the member 12, as by placing the foot thereon, and in this way the toggle-joint 7 is forced below the center, so to speak, or below the line $x-x$ which represents the straight line of thrust passing 95 100

through the pivotal points 2 and 5 of the shoes. The foot-piece 12 engages the top of the arm 3, to limit this movement of the toggle-joint below said line, so that the 5 trench jack is thus retained in its operative position. However, pressure exerted upward at the bottom of the toggle-joint, if sufficient, will force the joint above said line $\alpha-\alpha$, and then the trench jack will collapse, 10 as shown in dotted lines in Fig. 1, and may be lifted out of the trench. For trenches of different widths, the bolts 7 and 9 are adjusted to different holes 10 and 11 in the two toggle-arms 3 and 6, so that the jack 15 may be adjusted in length to suit the requirements.

Thus it will be seen that a very powerful device is provided for use as a transverse brace between the side walls of the trench. It 20 can be operated by downward pressure of the foot, or by resting a heavy object thereon, and is easily adjusted in position and removed from the trench. The device is not liable to get out of order, as it will operate even when badly rusted. Also, it can be manufactured at comparatively small expense.

The arms 3 and 6 can be of any suitable character, but as a matter of further and 30 special improvement, they are preferably constructed as follows:—The arm 3 is a section of pipe, and the arm 6 is of flat strap metal bent around so that this arm is, in effect, composed of two parallel portions 35 connected at their outer ends by the foot-piece or member 12, so that the upturned and united end portions of the arm 6 embrace the said section of pipe. The slide 8, with this construction, is preferably in the 40 form of a casting, as shown, having two depending ears for the bolt 7 by which the bifurcated arm 6 is pivoted thereon. This, it will be seen, insures a very strong construction.

45 Of course, when the bolt 9 is inserted in place, in the manner shown, it serves as means to keep the axis 7 of the toggle mechanism parallel with the axes 2 and 5 of the shoes 1 and 4, inasmuch as the slide 8 can- 50 not rotate on the pipe 3 when the bolt is thus inserted.

What I claim as my invention is:—

1. A trench jack comprising shoes to engage the opposite side walls of the trench, 55 a toggle connection between said shoes to force them away from each other, said toggle connection comprising an arm pivoted on each shoe, a slide on one arm, means to hold said slide in adjusted position on the 60 one arm, according to the width of the trench, means to pivot the other arm between its ends on said slide, so that the arm thus pivoted on said slide serves as a lever

by which to operate said toggle, and a stop on the end of said pivoted arm to rest on 65 said one arm when the toggle is forced downward.

2. A trench jack comprising shoes to engage the opposite side walls of the trench, 70 and a toggle connection between said shoes to force them away from each other having means to keep the axis of the toggle parallel with the axes of said shoes, said toggle connection having a foot-piece to force the toggle downward and serving as means to limit 75 this movement of the toggle joint below the line of thrust ($\alpha-\alpha$) between the pivots (2 and 5) of the shoes.

3. A trench jack comprising shoes to engage the opposite side walls of the trench, 80 a toggle connection between said shoes to force them away from each other, said toggle connection comprising an upper arm pivoted on one shoe, a lower arm pivoted on the other shoe, a slide on the 85 upper arm, means to hold the slide in adjusted position on the upper arm, means to pivot the lower end of the slide in different positions on said lower arm, and a foot-piece on the arm adjustably pivoted on the slide, 90 the two arms being substantially parallel when said foot-piece is resting on top of said upper arm.

4. A trench jack comprising a pair of shoes to engage the opposite side walls of 95 the trench, mechanism to force the shoes apart, operatively connected thereto having means to keep the axes of said shoes parallel, and a member to receive downward pressure thereon and connected to operate said mech- 100 anism.

5. A trench jack comprising a pair of shoes to engage the opposite side walls of the trench, mechanism to force the shoes apart, operatively connected thereto having 105 means to keep the axes of said shoes parallel, a member to receive downward pressure thereon and connected to operate said mechanism, said mechanism including a pivoted lever, and said member being a foot-piece on 110 an upturned portion forming a guide on the free end of said lever.

6. A trench jack comprising a pair of shoes to engage the opposite side walls of the trench, and mechanism to force the 115 shoes apart, operatively connected thereto, including a member to receive downward pressure thereon, connected to operate said mechanism, and two parallel portions which are pivoted to form an arm which swings up 120 and down, with said member forming a rigid connection between said portions at the free end of said arm.

7. A trench jack comprising shoes to engage the opposite side walls of the trench, 125 a toggle connection between said shoes to

force them away from each other, said toggle connection comprising an arm pivoted on each shoe, a slide on one arm, means to hold said slide in adjusted position on the 5 arm, according to the width of the trench, means to pivot the other arm on said slide, and a stop on said other arm to rest on said one arm when the toggle is forced down-

ward, said one arm consisting of a section of pipe, and said other arm being composed 10 of two parallel sections rigidly connected together at one end by said stop.

Signed by me at Chicago, Cook county, Illinois, this second day of January, 1918.

JAMES C. FRENCH.
